UNITED STATES PATENT OFFICE.

JOHN J. HOLLAND, OF NEW ORLEANS, LOUISIANA.

COMBINED SHOVEL AND SHIELD.

SPECIFICATION forming part of Letters Patent No. 291,782, dated January 8, 1884.

Application filed May 28, 1883. (No model.)

To all whom it may concern:

Be it known that I, JOHN J. HOLLAND, of New Orleans, in the parish of Orleans and State of Louisiana, have invented a new and

5 Improved Shovel and Shield, of which the following is a full, clear, and exact description.

The object of my invention is to provide in small compass, and so as to be conveniently 10 portable, a shovel and shield, and by a novel construction of the shovel-handle a receptacle for conveyance of small articles of utility, the devices being adapted, in their varying 15 adjustments, for use interchangeably by military men, tourists, and others.

The invention consists of a shovel-blade adapted to be quickly fixed in the slotted end of a handle, for uses of defense in war by throwing up intrenchments, as breast-works, 20 rifle-pits, &c., and for road-making and prospecting, the shovel-blade, when so adjusted, being capable of use in any ordinary manner, and by its combination with a sling bag or pouch the blade may be used as a breast-plate 25 in battle, the handle of the shovel being formed in hollow sections, adapting it for the reception and carriage of any small implements—such as eating-utensils or toilet articles—a sling-pouch being also provided for carrying 30 the dismembered handle-sections from a body-belt or other clothing attachment, as a button, the whole being capable of quick and interchangeable adjustments for the various uses to which it is adapted, all as hereinafter fully 35 described and claimed.

Reference is to be had to the accompanying drawings, forming part of this specification, in which similar letters of reference indicate corresponding parts in all the figures.

40 Figure 1 is a sectional side view of my improvement adjusted for use as a shovel. Fig. 2 is an elevation at right angles to Fig. 1, and partly broken away. Fig. 3 is a face view of the pouch with the dismembered handle placed or 45 packed therein, and Fig. 4 is a face view of the shovel-pouch with the sling-strap broken away.

The shovel-blade A, which may take the form of a shield, with any suitable device or 50 coat-of-arms stamped in or on it, is notched, as at a, centrally of its upper edge, and bored at

a', below notch a, for securing it to the handle, and holes a' are provided at the outer upper corners of the blade A, for locking it in its pouch, as hereinafter described.

55

The shovel-handle B is made in two or more hollow or tubular sections, b b', the lower section, b, having the long hard wood plug c rigidly fixed therein by one or more bolts, c', the lower section and plug being slotted suitably 60 to receive the shovel-blade A, whose notch a' embraces the bolt c', to serve with the removable thumb-screw or bolt c', which passes through the handle and blade A, to firmly secure the blade to the handle, and so as to 65 readily be removed or applied, the screw c' engaging a threaded nut, c', soldered or otherwise fixed to the section b, as shown in Fig. 2. The lower section, b, has any suitable cork or other internal stopper, d, fitted, if desired, with 70 a full cord, d', by which to remove the stopper, the size of section b permitting upper section, b', to be lapped or passed upon its head or upper end to joint telescopically with the lower section, b, said upper section, b', having 75 any suitable internal bottom, e, which may be rigidly fastened therein, so as to form a head to take the thrust of working the shovel-blade A into the earth, the upper section, b', having any suitable cap or cover, e', fitting tightly 80 thereon, but so as to readily be removed for filling the upper section with eating-utensils or other suitable implements or articles, the cover e', when removed, serving also as a goblet from which to drink. The lower section, 85 b, when the handle is jointed in working position, is stoppered by the upper section, b', as in Fig. 1; but the stopper d of the section b is preferred in use, as it affords a cover or protection for the utensils or implements which 90 may be stowed away in the lower section when the sections b b' are disjointed and packed away for convenient transportation in the pouch C, Fig. 3, which has a sling-loop, c', through which a body-belt may be passed for carrying 95 the handle by the belt.

Fig. 4 represents the sling bag or pouch for the shovel-blade A, said pouch consisting of a back plate or piece of metal or suitable fabric, D, having the leather or metal edge frame D' secured by a fastening of stitching, f, or otherwise, near the outside edge, so that the loose

inner edges of frame D' serve to hold the blade A between them and the back piece, D, as in a pocket, and without concealing the emblem or design on the face of the blade, which, when 5 thus placed in the pouch D D', with the hook or other button-head fastenings, g, of the sling-strap h passed through the pouch and through the corner holes, a², of the blade A, serves to hold and lock the blade in the pouch, and by 10 then suspending the pouch from about the neck or shoulders by the straps h the blade is made to serve as an effective shield or guard of vital parts of the wearer against injury by the missiles of small-arms or the sword or 15 bayonet. The blade, being of steel of a quality and strength to serve this purpose, together with its uses as a shovel and the pouch D D', serves also as a protection to the cutting-edges of the blade A, and prevents soiling the cloth- 20 ing after use of the blade, and may have any suitable tab, i, for better securing it over a button of the clothing.

Thus constructed, my improvement may not only be utilized as a shield and carrier for 25 small articles, but may very quickly be adjusted in emergencies to serve as an effective shovel for constructing earth-works for defense, or for any desired uses of the prospector or tourist.

Having thus described my invention, I claim 30 as new and desire to secure by Letters Patent—

1. A combined shovel and shield constructed with a sectional handle and a removable blade secured in a slot of the handle, substantially as shown and described. 35

2. The combination, with the blade A and handle B, formed of hollow sections b b', of the pouch C, for the handle-sections, and the pouch D D', for the blade, substantially as shown and described. 40

3. The combination, with the handle-section b, slotted to receive the blade A, of the fixed pin c' and the thumb-screw c² and nut c³, substantially as shown and described. 45

4. The sectional tubular handle, constructed of section b, having bottom plug, c, slotted to receive the shovel-blade, and fitted with a removable stopper, d, and the section b', having a rigid bottom, e, and a cap, c', substantially as shown and described. 50

5. The pouch D D', combined with the strong strap h, having hook-connections g which pass through the apertures a² of the blade A when it is adjusted as a shield, substantially as shown and described.

JOHN J. HOLLAND.
